Filed Feb. 4, 1960, Ser. No. 6,717
13 Claims. (Cl. 307—64)

My invention relates to an apparatus for automatically connecting an electrical load to a second or emergency source of supply when the preferred or regular source of supply fails.

More particularly, my invention relates to an apparatus responsive to a failure of a predetermined condition or voltage failure of a preferred supply to connect the electrical load to an emergency supply. My apparatus is particularly adapted for electrical installations which require a high degree of service reliability. Hospitals, public buildings, military establishments and the like are a few examples of areas in which my invention may be utilized. There are in use today numerous types of apparatus capable of performing the operation for which my invention is designed. The industry for years, however, has searched for a system of the required high standard of reliability capable of being manufactured and installed at a lower cost. The requirements to be met by such a system are well established in the industry. Most important, is the requirement of faultless operation with safety.

My invention is designed to include a minimum number of operating parts, to provide an easily movable and installable unit in presently existing circuit interrupter arrangements, to enable periodic testing with minimum down-time and engineering complications, and to provide a unit which may be manufactured and installed at a reasonable cost.

When installed my apparatus is connected to the usual circuit interrupters or switches which are capable of being manually operated. Circuit interrupters without operating handles can be easily adapted for use with my apparatus.

Switch means enable the selective connection of a load with the preferred supply or an emergency supply; a plurality of emergency supplies can be utilized with suitable modifications. Transfer means responsive to a predetermined condition such as failure or radical changing of preferred voltage accomplishes the change-over as will be described. Fluid powered means, preferably gas though hydraulic systems may be used, are used, a fluid driven preferred ram driving the preferred switch and a fluid driven emergency ram the emergency switch.

To prevent change-over when a voltage fluctuation has a short life, a time delay means is included which delays flow of fluid through the gas supply system for a predetermined period of time, which is adjustable.

A solenoid controlled gas valve responds to the voltage fluctuation and controls gas flow to the preferred ram which includes a piston and cylinder, the preferred switch being connected to the piston. Suitable controls are provided for sequential actuation of the similar emergency ram. Further, as will be explained, my invention can be employed to automatically as well as manually return the load to the preferred supply upon return of power thereto either by paralleling the supplies or by opening the emergency switch and then closing the preferred switch.

When the manual return system is used only one electrical device is utilized in the switch change-over apparatus. The apparatus is mechanically reversible by simple relocation of the operating units; this reversibility feature permits continued use of the same transfer device if supply feeders are reversed.

Other important objects and advantageous features of the invention will be apparent from the following description and accompanying drawings, wherein, for the pur-

2

poses of illustration herein, a specific embodiment of this invention is set forth in detail, and wherein:

FIG. 1 is a perspective view of my apparatus including portions of the preferred feeder operating rod and the emergency feeder operating rod;

FIG. 2 is a perspective view similar to FIG. 1 with the operating rods in their other positions and with the rams disconnected therefrom and tilted to a horizontal position for inspection and testing;

FIG. 3 is a schematic view showing the apparatus of FIGS. 1 and 2 connected to the electrical system;

FIG. 4 is a schematic view of an embodiment of my invention providing automatic return to preferred supply by paralleling the two supplies; and

FIG. 5 is a schematic view of another embodiment of my invention providing automatic return to preferred supply by first opening the emergency supply and then closing the preferred supply.

Referring now to FIGS. 1, 2, and 3, it will be seen that the apparatus of my invention includes a fluid operating system, the pneumatic or gas system shown being preferred. A frame 70 is provided which includes a base 71 on which are mounted two operating rams 20 and 21 through pivoted connections 72 and 73 which enable each ram to assume the required angular attitude during actuation of the operating rods 74 and 75. A support 76 is also provided at the base for a bottle 1 of gas, this bottle having a cut-off valve and a pressure regulator 2, the gas then passing through the main gas supply system 60 to a main gas valve 4 which, in the preferred embodiment, takes the form of a three-way solenoid operated valve. This valve 4 as seen in FIG. 3 is electrically connected to the utilization voltage, this being the voltage supplied to the load such as a hospital. On failure of utilization voltage the solenoid will be released and the valve 4 will open.

The term "three-way valve" when used in this application defines a valve which allows downstream passage from one conduit to another, stops upstream passage between the lines, and provides when closed for venting of back pressure present downstream of the valve through a vent 90 (FIG. 3).

The gas preferably then flows past a manual vent valve 3 to a time delay means 8 which delays activation of the rams a predetermined time to prevent change-over of switches due to only split second voltage failure. This time delay means 8 includes a variable orifice 5 adjustable by a knob, a gas reservoir 6 downstream thereof, followed by a three-way pilot valve 7, the vent 90 to atmosphere being responsive to back pressure upon closing of the pilot valve 7 being provided to vent the cylinders and the lines. Gas flows from the time delay means 8 to the upper end of preferred ram 20 and the piston therein is forced downwardly with air venting through outlet 91. When the preferred ram 20 reaches its lowermost open position, actuator 10 mounted on the ram 20 engages three-way sequence valve 9 to allow gas to flow through the main gas supply system 60 to the lower end of emergency cylinder whereby the emergency ram 21 is forced upwardly to close the switch and connect the load to the emergency supply.

It will be noted in FIGS. 1 and 2 that the frame 70 includes a back plate 77 to which the preferred actuation arm 78 and the emergency actuation arm 79 are pivotally mounted through angle brackets 80. Mounting holes 81 are provided in the back plate 77 for attachment of the apparatus to foundation bars, not shown. Any suitable technique of anchoring the apparatus may be used. The preferred operating rod 74 and the emergency operating rod 75 are pivotally mounted about midway along the length of the operating arms 78 and 79 and the rams 20 and 21 are pivotally mounted near the outer end por-

tions. Suitable removable pins held by locking rings may be used to facilitate disassembly. Sockets 33 are provided at the ends of both arms 78 and 79 for receiving a lever to enable manual switching.

OPERATION

Assuming loss of voltage from the normal or preferred supply due to failure, the system will function as follows:

(1) Solenoid valve 4 will open, permitting gas to flow into the main gas supply system 60.

(2) Gas pressure is immediately available to pilot valve 7 but cannot pass therethrough until a predetermined time elapses for the gas to pass through variable orifice 5 and gas reservoir 6 whereby sufficient pressure is built up over the spring biased piston in pilot valve 7 to cause downward movement thereof and open the pilot valve to permit gas therethrough. The spring indicates schematically the force which must be overcome.

(3) When pilot valve 7 opens, gas flows through the by-pass line 25 of the time delay means 8 to closed three-way sequence valve 9 and to the upper end of the preferred ram 20 which is attached to the circuit interrupter or switch 100 of the preferred supply. Upon downward movement of the preferred ram 20, actuator 10 opens sequence valve 9 upon the ram reaching its open position at the end of its downward stroke.

(4) When valve 9 opens, gas flows to the lower end of the emergency ram 21 causing the emergency ram 21 to move upward and thereby closing the emergency switch 101 and energizing the load circuit, thus restoring utilization voltage to gas valve 4.

(5) Restoration of utilization voltage causes gas valve 4 to close and shut off the flow of gas in the main gas supply system 60. The residual gas in the rams and gas lines will automatically vent to atmosphere through the vent 90 in pilot valve 7, and the vent 90 in solenoid valve 4.

When the preferred supply becomes available again, the operator may manually change-over the switches 100 to 101 to reconnect the load to the preferred supply. All manual switching operations, except one, may be directly performed by an attendant without regard to the automatic transfer device. The one exception occurs only if both sources of supply fail. The device will then operate needlessly and fill the system with gas pressure which cannot vent to atmosphere through valve 4 or pilot valve 7 because utilization voltage is not restored. Under such circumstances the system may be vented manually to atmosphere through vent valve 3.

The apparatus is applicable to operations of all circuit interrupter devices with manual operating handles. With suitable modifications, it can be adapted to operate the controls of circuit interrupters without operating handles.

FIGURE 4

Apparatus for automatically returning the switches to normal condition by paralleling the preferred supply with the emergency supply is shown schematically in FIGURE 4. Similar portions of FIGURE 4 to FIGURES 1, 2 and 3 carry similar numerals. This apparatus enables automatic return without interrupting the load circuit.

It will be noted that the main gas supply system 60 is similar to that previously discussed and also includes a solenoid operated three-way stop valve 16 upstream of the previously discussed time delay means 8, valve 16 being normally closed and openable upon failure not of load or utilization voltage but of preferred supply voltage.

A secondary gas supply system 110 is also provided to supply the power for return of the rams to normal position, this system 110 being shown in pneumatic parallelism with the main system 60. A secondary gas valve 17 is placed upstream of a solenoid operated control valve 15 which is in turn upstream of a time delay means 48 which is similar to time delay means 8.

The secondary gas valve 17 is normally open and closes

upon failure of utilization or load by means of the electrical connections shown.

The control valve 15 is electrically connected to a standard micro-switch 12 which connects the solenoid of the valve 15 to the preferred supply voltage transformer 120 when the emergency ram 21 is in closed position placing the emergency switch 101 in closed condition. A knee action micro-switch 13 is provided for actuation by the emergency ram 21 when it is returned to open position to pulse the control valve 15 and cause valve 15 to close. The other elements of the apparatus are the same as FIGURE 3. Assuming loss of utilization or load voltage associated with failure of the preferred source of supply, the transfer system will function as follows:

(1) Valve 4 and valve 16 will open permitting flow of gas through the main gas supply system 60.

(2) Gas pressure is immediately available to closed pilot valve 7 but gas cannot pass through it until sufficient time elapses (time delay) for gas to pass through variable orifice 5 and gas reservoir 6 and thence open pilot valve 7 to permit flow of gas through it.

(3) When pilot valve 7 opens, gas pressure becomes available to closed valve 9 and to ram 20 attached to rod 74 and switch 100 in the preferred supply. Ram 20 will move downward transmitting corresponding motion to open the attached circuit interrupter 100 in the preferred supply. When the ram 20 reaches the end of its downward stroke and open position, mechanical actuator 10 will cause valve 9 to open.

(4) When valve 9 opens, gas pressure becomes available to ram 21 attached to rod 75 and switch 101 in the emergency supply. Ram 21 will move upward transmitting corresponding motion to close the attached circuit interrupter 101 in the emergency supply and restore load voltage to valve 4 and reenergize the load circuit.

(5) Restoration of load voltage will cause valve 4 to close and shut off the flow of gas. The residual gas in the rams 20, 21 and gas lines beyond valve 4 will automatically vent to atmosphere through vents 90 in pilot valve 7 and gas valve 4, stop valve 16 and sequence valve 9.

When the condition which caused the preferred supply to fail has been remedied and voltage is restored thereto, the return of the load to the preferred supply occurs as follows:

(6) Preferred voltage through micro-switch 12 will open control valve 15 permitting gas to flow through the secondary gas supply system 110. The flow of gas is controlled and directed to cause the rams 20, 21 to move in a desired order.

(7) Gas pressure is immediately available to closed pilot valve 47 and preferred ram 20. Gas cannot pass through pilot valve 47 until sufficient time elapses (time delay) for gas to pass through variable orifice 45 and gas reservoir 46 and thence open pilot valve 47 to permit flow of gas through it. Before pilot valve 47 opens, the preferred ram 20 will move upward transmitting corresponding motion to close the attached switch 100 in the preferred supply and parallel the supplies.

(8) When pilot valve 47 opens, gas pressure becomes available to ram 21. The ram 21 will move downward transmitting corresponding motion to open the attached switch 101 in the emergency supply and separate the supplies.

(9) As ram 21 approaches the end of its downward movement and open position its attached mechanical actuator 30 will momentarily contact knee action micro-switch 13 and establish a pulse of preferred supply voltage to close control valve 15 and shut off the gas at this point.

(10) The residual gas in the rams and gas lines beyond control valve 15 will automatically vent to atmosphere through vents 90 in control valve 15, and pilot valve 47. The apparatus is now reset to its normal position and awaiting another condition causing failure of the preferred supply.

Conditions pertaining to failure of both sources of supply

A needless transfer of the load from the preferred supply to the emergency supply will occur. Restoration of the load will depend on which source of supply first has voltage restored thereto.

Voltage restored first to emergency supply

(1) The load is immediately restored and load voltage will cause gas valve 4 to close and secondary gas valve 17 to open. The residual gas in the rams and gas lines past gas valve 4 will automatically vent to atmosphere through valve 4 and valve 7 and the apparatus awaits restoration of voltage to the preferred supply. Upon restoration of this voltage the apparatus will operate as described in immediately above items (6), (7), (8), (9) and (10).

Voltage restored first to preferred source of supply

The load cannot be restored to service because the automatic transfer device is locked out by closed secondary gas valve 17. Automatic venting will occur at stop valve 16 and pilot valve 7 when the preferred supply is restored. To restore the load to the preferred supply it will then be necessary to perform manual operations. The order of manual switching, as follows, of the switches 100, 101 must be adhered to in order to avoid complete interruption if the condition on the emergency supply has not been remedied:

(1) Manually opens switch 101 in the emergency supply.

(2) Manually close switch 100 in the preferred supply to restore the load and load voltage to close gas valve 4 and open secondary gas valve 17. The apparatus is now reset to its normal position and awaiting another condition causing failure of the preferred supply.

The time delay means 48 as indicated in FIGURE 4 is used to assure full motion of preferred ram 20 before any motion of emergency ram 21. The time delay means 48 may be replaced by a valve same as sequence valve 9 if the valve is physically located so as to be opened when ram 20 reaches the end of its upward stroke. If it is desired to have the preferred supply remain alive for a predetermined time before initiating transfer from emergency supply to preferred supply, a time delay means similar to means 48 is required between control valve 15 and ram 20.

FIGURE 5

The apparatus of FIGURE 5 is designed to enable automatic return by first opening switch 101 in the emergency supply and then closing switch 100 in the preferred supply. Referring now to FIGURE 5, and assuming loss of load voltage associated with failure of the preferred supply, the apparatus will function as follows:

(1) Gas valve 4 and stop valve 16 will open permitting flow of gas through the main gas supply system 60. The flow of gas is controlled and directed to cause the rams 20 and 21 to move in a desired order.

(2) Gas pressure is immediately available to closed pilot valve 7 but gas cannot pass through it until sufficient time elapses (time delay) for gas to pass through variable orifice 5 and gas reservoir 6 and thence open pilot valve 7 to permit flow of gas through it.

(3) When pilot valve 7 opens, gas pressure becomes available to closed sequence valve 9 and to preferred ram 20 attached to switch 100 in the preferred supply. Ram 20 will move downward transmitting corresponding motion to open the attached switch 100 in the preferred supply. When ram 20 reaches the end of its downward stroke, mechanical actuator 10 will cause sequence valve 9 to open.

(4) When sequence valve 9 opens, gas pressure becomes available to emergency ram 21 attached to switch 101 in emergency supply. Ram 21 will move upward transmitting corresponding motion to close the attached switch 101 and restore load voltage to gas valve 4 and reenergize load circuit.

(5) Restoration of load voltage will cause gas valve 4 to close and shut off the flow of gas. The residual gas in the cylinders and gas lines (beyond valve 4) will automatically vent to atmosphere through vents 90 in pilot valve 7 and gas valve 4.

When the condition which caused the preferred supply to fail has been remedied and voltage is restored thereto, the return of the load to the preferred supply occurs as follows:

(6) Preferred supply voltage through micro-switch 12 will open control valve 15 permitting gas to flow through another gas supply system 105. The flow of gas is controlled and directed to cause the rams 20, 21 to move in a desired order. As preferred supplying voltage becomes available to micro-switch 12, it also becomes available to close stop valve 16.

(7) Gas pressure is immediately available to closed pilot valve 47. Gas cannot pass through pilot valve 47 until sufficient time elapses (time delay) for gas to pass through variable orifice 45 and gas reservoir 46 and thence open pilot valve 47 to permit flow of gas through it.

(8) When pilot valve 47 opens, gas pressure becomes available to closed throw valve 29 and to ram 21 attached to switch 101 in emergency supply. Ram 21 will move downward transmitting corresponding motion to open the attached switch 101 in the emergency supply. When ram 101 reaches the end of its downward stroke mechanical actuator 14 will cause throw valve 29 to open.

(9) When valve 29 opens, gas pressure becomes available to preferred ram 20. Ram 20 will move upward transmitting corresponding motion to close switch 100 in the preferred supply and restore load voltage to gas valve 4 and reenergize the load circuit.

(10) As ram 20 approaches the end of its upward movement its attached mechanical actuator 10 will momentarily contact knee action micro-switch 23 and establish a pulse of preferred supply voltage to close control valve 15 and shut off gas at this point.

(11) The residual gas in the rams and gas lines (beyond control valve 15) will automatically vent to atmosphere through vents 90 in control valve 15 and pilot valve 47. The apparatus is now reset to its normal position and awaiting another condition causing failure of the preferred supply.

Conditions pertaining to failure of both sources of supply

(12) A needless transfer of the load circuit from the preferred supply to the emergency supply will occur. Restoration of the load circuit will depend on which source of supply first has voltage restored thereto.

Voltage restored first to emergency supply

(1) The load circuit is immediately restored and load voltage will cause gas valve 4 to close. The residual gas in the rams and gas lines beyond gas valve 4 will automatically vent to atmosphere through vents 90 in valve 4 and pilot valve 7 and the apparatus awaits restoration of voltage to the preferred source of supply.

Voltage restored first to preferred supply

(1) Upon restoration of voltage to the preferred supply, the apparatus will operate in items (6), (7), (8), (9), (10) and (11) immediately above.

In the claims, the pilot valves 7 and 47 of the time delay means 8 and 48 respectively are identified as "threshold pressure valves" for clarity.

The embodiments of the invention in which an exclusive property or privilege is claimed are defined as follows:

I claim:

1. In electrical apparatus, an electrical load, an electrical preferred supply, an electrical emergency supply,

switch means connected to said load and normally connecting said load to said preferred supply, transfer means connected to said switch means and responsive to a predetermined condition of said preferred supply to disconnect said switch means from said preferred supply and to connect said switch means to said emergency supply, said transfer means having a fluid powered means for actuating said switch means, and wherein said switch means includes a preferred switch and an emergency switch engageable with the preferred supply and the emergency supply respectively; said fluid powered means including a gas driven preferred ram and a gas driven emergency ram operably associated with their respective preferred and emergency switches, said transfer means including a gas supply system operably associated with the rams including a gas valve responsive to and openable upon loss of preferred voltage to the load, to allow gas flow to said preferred ram to move the ram and open said preferred switch, a sequence valve in said gas supply system responsive to the opening movement of said ram to enable gas flow to said emergency ram to move the ram and close said emergency switch.

2. In electrical apparatus as defined in claim 1 and wherein said transfer means includes a time delay means in said gas supply system downstream of said gas valve to delay preferred ram movement for a predetermined time period.

3. In electrical apparatus as defined in claim 2 and wherein said time delay means includes a by-pass line, a variable orifice valve followed by a gas reservoir followed by a threshold pressure valve which at a predetermined threshold pressure opens said by-pass line around the above for gas flow to the rams.

4. In electrical apparatus as defined in claim 3 and wherein said gas supply system includes a vent valve downstream of said gas valve to facilitate manual operation of the rams.

5. In a device for actuating a preferred switch and an emergency switch to change-over an electrical load from a preferred supply to an emergency supply in response to a predetermined condition, comprising transfer means having a fluid driven preferred ram adapted to be operably associated with said preferred switch and a fluid driven emergency ram adapted to be operably associated with said emergency switch, a main gas supply system operably associated with the rams including a main gas valve upstream thereof responsive to and openable upon said predetermined condition to allow gas flow to said preferred ram to move the ram to enable opening of the preferred switch, a sequence valve in said gas supply system responsive to the opening movement of said ram to enable gas flow to said emergency ram to move the ram to enable closing of said emergency switch.

6. In a device in accordance with claim 5 and wherein said transfer means includes a time delay means in said gas supply system downstream of said gas valve to delay preferred ram movement for a predetermined time period.

7. In a device in accordance with claim 6 and wherein said time delay means includes a by-pass line, a variable orifice valve followed by a gas reservoir followed by a threshold pressure valve which at a predetermined threshold pressure opens said by-pass line around the above for gas flow to the rams.

8. In a device in accordance with claim 7 and wherein said gas supply system includes a vent valve downstream of said gas valve to facilitate manual operation of the rams.

9. In a device in accordance with claim 5 wherein said predetermined condition is a failure of load voltage and wherein said main gas supply system includes a stop valve upstream of said preferred ram normally closed and openable upon failure of preferred supply voltage, a secondary gas supply system for returning the rams to normal condition including a secondary gas valve responsive to and openable upon failure of load voltage, a control valve downstream of said secondary gas valve responsive to closing movement of said emergency ram and preferred supply voltage to allow gas flow to said preferred ram to return the ram to closed position and to allow gas flow to said emergency ram to return the ram to open position, a secondary time delay means between said control valve and said emergency ram to delay gas flow to the ram until the preferred ram reaches closed position, said control valve being responsive to movement of the emergency ram to open position to stop gas flow.

10. In a device in accordance with claim 9 and wherein said main gas supply system includes a time delay means downstream of said gas valve and said stop valve to delay preferred ram movement for a predetermined time period.

11. In a device in accordance with claim 5 wherein said predetermined condition is a failure of load voltage and wherein said main gas supply system includes a stop valve upstream of said preferred ram normally closed and openable upon failure of preferred supply voltage, another gas supply system for returning the rams to normal condition including a control valve responsive to closing movement of said emergency ram and preferred supply voltage to allow gas flow to said emergency ram to return the ram to open position, a throw valve between said another gas supply system and said preferred ram and openable in response to return to open position by said emergency ram, said control valve being responsive to movement of the preferred ram to closed position to stop gas flow.

12. In a device in accordance with claim 11 and wherein said main gas supply system includes a time delay means downstream of said gas valve and said stop valve to delay preferred ram movement for a predetermined time period and wherein said another gas supply system includes another time delay means between said control valve and said throw valve.

13. In a device in accordance with claim 5 wherein said predetermined condition is a failure of load voltage and wherein said main gas supply system includes a stop valve upstream of said preferred ram normally closed and openable upon failure of preferred supply voltage, a secondary gas supply system for returning the rams to normal condition including a secondary gas valve responsive to and openable upon failure of load voltage, a control valve downstream of said secondary gas valve responsive to closing movement of said emergency ram and preferred supply voltage to allow gas flow to said preferred ram to return the ram to closed position and to allow gas flow to said emergency ram to return the ram to open position, means operatively associated with said control valve and said emergency ram to delay gas flow to the ram until the preferred ram reaches closed position, said control valve being responsive to movement of the emergency ram to open position to stop gas flow.
